UNITED STATES PATENT OFFICE.

CHARLES KRAMER, OF CARBONADO, WASHINGTON.

DESIGN FOR A COLLAR.

60,619.

Specification for Design.

Patented Mar. 14, 1922.

Application filed September 27, 1920. Serial No. 413,252. Term of patent 7 years.

To all whom it may concern:

Be it known that I, CHARLES KRAMER, a citizen of the United States, residing at Carbonado, in the county of Pierce, State of Washington, have invented a new, original, and ornamental Design for a Collar, of which the following is a specification, reference being had to the accompanying drawing, forming part thereof.

I claim:

The ornamental design for a collar as shown.

CHARLES KRAMER.
